UNITED STATES PATENT OFFICE.

ILIA EMMANUEL MOUROMTSEFF, OF WILKINSBURG, PENNSYLVANIA, ASSIGNOR TO WESTINGHOUSE ELECTRIC & MANUFACTURING COMPANY, A CORPORATION OF PENNSYLVANIA.

VACUUM-TUBE DEVICE.

Application filed April 28, 1925. Serial No. 26,340.

My invention relates to vacuum-tube devices and particularly to structural details of such devices which are adapted for the translation of relatively high electrical energy values.

An object of my invention is to provide a high-power oscillator triode with a grid lead which is capable of carrying a substantial amount of current.

Another object of my invention is to provide a grid lead construction adapted for convenient insertion through a seal.

Another object of my invention is to simplify the structural details of vacuum-tube devices.

In the prior art, triode tubes have been constructed which are adapted to the translation of power as great as 10 kw. of electrical energy. These triode devices are adapted to the generation of radio-frequency oscillations. Such devices function adequately at frequencies of the order of about 1500 kilo-cycles per second without particular difficulty, but at higher frequencies of generation difficulty has been experienced in leading to the grid, or control electrode, the necessary charging current to cause the operation of generation to take place.

The tubes as previously constructed, were built with a wire conductor sealed through a portion of the glass container. Within the container, a coiled flexible wire of smaller diameter was attached to the seal wire and was also attached to a wire leading to the grid structure. The operation of sealing the conductor through the glass required that a portion of the lead within the container be flexible. This was conveniently attained by the coiled wire mentioned.

However, when the triode was used for the generation of frequencies above the order of about 1500 kilo-cycles, the small size and coiled character of this wire resulted in the generation of an undesirable amount of heat therein by reason of ohmic losses, eddy currents, and the "skin effect" in the coiled conductor.

My invention provides a simplified, flexible grid lead which is adapted to be conveniently sealed through the glass of the container, and which has a sufficiently high conductivity to reduce losses to such value

that difficulty with heating is not experienced.

Other objects and structural details of my invention will be apparent from the following description when read in connection with the accompanying drawing wherein,

Figure 1 is a view in vertical sectional elevation of a triode containing an embodiment of my invention; and

Fig. 2 is a detail view of the flexible portion of a grid lead therein.

Referring to the figures, a metal shell 65 electrode 1 is attached to a glass closure 2 by a seal 3. Within the metal shell 1 is positioned a filamentary cathode 4 and a control electrode 5 having a supporting member 6 clamped to a re-entrant portion 7 70 of the closure 2. To the control electrode support 6 is attached a conductor 8. A conductor 9 is suitably sealed through the wall of the glass closure 2. Connection is made between the conductors 8 and 9 by a number 75 of strips 11 preferably flattened and of conducting material which may be connected, as by spot welding, at their respective ends to the conductors 8 and 9 and may be further held in position by wire wrappings 80 12 and 13.

The conductors 8 and 9 are preferably of tungsten or molybdenum and the connector portions 11 are preferably strips of molybdenum. The binding wires 12 and 13 are 85 also preferably of molybdenum.

The strips of molybdenum offer sufficient conductivity to the current to permit conduction therethrough without excessive resistive losses. Likewise, the fact that the 90 conductive pieces are bent through only a portion of a turn instead of being coiled as was previously done removes the inductive action which produced the "skin effect" in prior constructions, resulting in increased 95 losses. My construction also reduces the eddy currents and thus removes a large part of such losses. Thus, the conductive lead is maintained at a satisfactory temperature during operation of the tube.

In the assembly of the device, the flexibility of the strips of material 11 is sufficient to permit the construction of a satisfactory seal for the conductor 9 through the glass 2.

By means of this construction, I am en-

abled to simplify the manufacture of a vitreous portion, and a lamellar connection between the inner end of said lead and said control electrode.

20

While I have shown but a single embodiment of my invention, it is capable of various modifications thereof and it is desired, therefore, that only such limitations shall be imposed thereon as are required by the prior art or indicated in the appended 10 claims.

25

I claim as my invention:

1. In a space current device, the combination of a container comprising a metallic portion and a vitreous portion, said metallic portion comprising an anode, a control electrode and a filamentary cathode within said 15 container, a lead sealed in a side wall of said

30

containing, a lead sealed in a side wall of said vitreous portion, and a connection between the inner end of said lead and said control electrode, comprising superposed laminations of molybdenum.

25

In testimony whereof, I have hereunto subscribed my name this 22nd day of April, 1925.

ILIA E. MOUROMTSEFF.
